UNITED STATES PATENT OFFICE.

HENRY MELVIN RENNER, OF TULSA, OKLAHOMA.

COLLAPSIBLE CUP.

Application filed November 8, 1921. Serial No. 513,679.

To all whom it may concern:

Be it known that I, HENRY M. RENNER, a citizen of the United States, residing at Tulsa, in the county of Tulsa and State of Oklahoma, have invented certain new and useful Improvements in a Collapsible Cup; and I do hereby declare the following to be a full, clear, and exact description of the invention, such as will enable others skilled 5 in the art to which it appertains to make and use the same.

This invention relates to a collapsible cup and the general aim is to provide a construction primarily adapted for individual 10 use to promote sanitation.

Another object is to provide a collapsible cup or receptacle having a nozzle frame tensioned to urge the cup into an expanded position, and one which may be made from 20 a single strand of wire and include a spring coil, and arms having the terminals thereof formed into handles and a means to fasten the handles against separation.

Another object is to provide an article of 25 this kind adapted to fit a container and in connection with which said handles cooperate to facilitate insertion and removal of the cup from the container.

Additional objects and advantages will 30 become apparent from a consideration of the description following taken in connection with accompanying drawings illustrating one practical embodiment.

In said drawings:—

35 Figure 1 is a side elevation of the device showing the cup within a container and with the closure section of the container raised;

Figure 2 is a side elevation of the cup 40 alone expanded for use;

Figure 3 is a side elevation of the cup in a collapsed condition; and

Figure 4 is a bottom or inverted plan view 45 of the cup.

Like reference numerals designate like or similar parts throughout the views of the drawings.

In reducing the invention to practice, an 50 imperforate, hollow inverted, substantially conical body is provided at 5 serving as a receptacle to contain water or other liquid. This body may be made of any suitable material for instance waterproof fabric.

Associated with the body 5 is a frame to 55 hold it expanded. Such frame may be made of any suitable material but prefer-

ably is constructed from a single strand of flexible metallic wire. This strand has elongated side arms 6 and 7 connected together by coils 8 forming a spring tensioned so as to normally urge the arms 6 and 7 to separate at their upper or free ends. At said ends, above the body 5, the arms 6 and 7 are formed into loops or handles 9. The terminals of said arms are 60 coiled as at 10 and one terminal extended and forms into a hook 11 adapted to engage the opposite arm, namely arm 7 in order to hold the arms 6 and 7 and the body 5 in collapsed or folded condition. 70

A suitable container or receptacle is provided which may consist of a body section 12 and a closure section 13 adapted to slide on to the upper or free end thereof to frictionally engage the same. The application 75 of the cover or closure 13 is limited by a bead at 14. Said cup in the collapsed condition referred to is adapted to be inserted within the section 12 and the handles 9 project above the upper end of said section 80 12 as shown in Figure 1, so as to facilitate engagement of the fingers therewith to remove the cup for use.

The article may be normally carried on the person of the user or owner, for instance 85 in the pocket, and at this end it may have a fastening clasp or clip as illustrated at 15 to clamp a portion of the pocket between it and the receptacle 12 to prevent loss thereof.

When the cup is to be used, closure 13 is 90 removed after which the handles 9 are grasped and lifted in order to remove the cup from the container. Thereafter the hook 11 is detached from the arm 7 and the spring 8 urges separation of the arms 6 95 and 7 at the handle end which will expand the body 5 into the position shown in Figure 2 in which it may be used as a cup for general purposes, particularly drinking.

As illustrated at 16, a suitable ornamental 100 design or advertisement may be delineated upon the body 5.

As merely one practical embodiment has been illustrated and described, it is to be understood that changes within the details 105 and principles may be resorted to provided they fall within the spirit and scope as defined in the appended claim.

I claim as my invention:—

A cup having a collapsible containing body, a frame associated therewith consisting of a resilient strand having arms to 110

large expansion of said body, the terminals of the strand being formed into open handles, one of said terminals continues from said handle and twisted around the strand and formed into a hook projecting beyond the strand and in a plane substantially at a right angle to the handle, and said hook adapted to detachably engage the opposite

arm below its handle to maintain said body in a collapsed condition. 10

In testimony whereof I affix my signature in presence of two witnesses.

HENRY MELVIN RENNER.
